UNITED STATES PATENT OFFICE.

SILAS SPARKS, OF PEARSON, OHIO.

GATE.

SPECIFICATION forming part of Letters Patent No. 350,165, dated October 5, 1886.

Application filed May 15, 1886. Serial No. 202,251. (No model.)

To all whom it may concern:

Be it known that I, SILAS SPARKS, a citizen of the United States, residing at Pearson, in the county of Fayette and State of Ohio, 5 have invented a new and useful Improvement in Gates, of which the following is a specification.

My invention relates to an improvement in swinging gates; and it consists in the peculiar 10 construction and combination of devices, that will be more fully set forth hereinafter, and particularly pointed out in the claim.

Figure 1 is a side elevation of a gate embodying my improvements. Fig. 2 is a trans- 15 verse horizontal sectional view of the same, taken on the line *x x* of Fig. 1. Fig. 3 is a horizontal section on line *y y*, Fig. 1. Fig. 4 is a detail view of the link *L*.

A represents the post to which the gate is 20 hinged.

B represents the post against which the gate closes.

C represents a supporting bar or standard, which is hinged to the post *A* by means of 25 hinges *D*. The said bar or standard *C* is vertical, and is provided on its inner side with a vertical series of ratchet-teeth, *E*.

F represents a gate, which is composed of the end bars, *G* and *G'*, the horizontal rails *H*, 30 and the inclined brace-rails *I*. This gate is secured to the standard *C* by means of straps or keepers *K* and *K'*, which are attached to opposite sides of the said standard and extend forward therefrom and bear on opposite sides 35 of the bars *G'*. The straps *K*, at the upper end of the standard *C*, have their outer ends of sufficient length to extend entirely across the sides of the bar *G'*, and are then bent in- 40 wardly at right angles, forming hooks *K''*, which engage the front edge of the bar *G'*. From this construction it will be readily understood that the gate is so attached to the standard *C* as to enable it to slide vertically on the said standard.

45 In order to secure the gate at any desired vertical adjustment, I provide a link, *L*, the lower end of which bears under one of the rails *H*, of the gate, and the upper end of which embraces the standard *C* and is adapted 50 to engage one of the teeth *E*. The gate is thus permitted to be raised for a suitable distance to enable small stock to pass under the gate, and also to enable it to clear snow-drifts.

It will be noted that the straps *K*, near the lower end of the standard *C*, bear only on the 55 sides of the bar *G'*, and do not engage the front edge thereof. This enables the gate to swing outwardly at its lower inner end from the standard *C*, thus permitting the gate to be tilted, and thereby restored to a horizontal position, in the event that the post *A* sags or becomes inclined.

The gate may be supported in any desired position by inserting a wedge or key, *M*, between the lower ends of the bar *G'* and the 60 standard *C*.

N represents a sliding latch, with which the gate is provided. The outer end of the said latch is adapted to engage a vertical groove, *b*, which is made on the inner side of the post *B*. 70

A gate thus constructed is cheap and simple, is strong and durable, and may be adjusted vertically in order to clear snow-drifts or permit small animals to pass under it.

No claim is made herein, broadly, for the 75 combination of the hinged standard and the gate attached thereto and vertically adjustable thereon, as this, I am aware, is not novel.

I am also aware that it has been heretofore proposed to provide the hinged standard with 80 straps on opposite sides thereof to embrace the vertical bar at the inner end of the gate, and this also, broadly, I disclaim.

Having thus described my invention, I 85 claim—

The combination of the hinged standard *C*, the straps *K* on opposite sides of the upper end thereof and having the hooks *K''*, the straps *K'* on opposite sides of the said standard, near the lower end thereof, the said straps *K'* being 90 without hooks, and the gate having the vertical bar *G'* at its inner end, the said bar being placed between the straps *K* and *K'* and engaged at its upper end, on its inner side, by the hooks *K''*, and the wedge or key adapted to be 95 inserted between the lower ends of the hinged standard *C* and the bar *G'*, for the purpose set forth, substantially as described.

In testimony that I claim the foregoing as my own I have hereto affixed my signature in 100 presence of two witnesses.

SILAS SPARKS.
